CLAIM

We claim the ornamental design for a mirror assembly, as shown and described.

DESCRIPTION

FIG. 1 is a top rear perspective view of a mirror assembly of the present disclosure;

FIG. 2 is a bottom rear perspective view of the mirror assembly of FIG. 1;

FIG. 3 is a rear elevational view of the mirror assembly of FIG. 1;

FIG. 4 is a first side elevational view of the mirror assembly of FIG. 1;

FIG. 5 is a second side elevational view of the mirror assembly of FIG. 1;

FIG. 6 is a top plan view of the mirror assembly of FIG. 1; and,

FIG. 7 is a bottom plan view of the mirror assembly of FIG. 1.

In the drawings, the broken lines depict portions of the article that form no part of the claimed design.
